CARTON EDGE PROTECTOR AND TIE
RETAINER DEVICE

Luis Ochoa Vizcaino, Guadalajara, Mexico

Application April 22, 1935, Serial No. 17,709
In Mexico May 23, 1934

5 Claims. (Cl. 229—46)

My invention relates to a carton edge protector and tie retainer device designed primarily for use in connection with cartons of the corrugated paper type, but it is to be understood that a device, in accordance with my invention, may be employed in any connection for which it is found applicable.

The essential objects of my invention are to provide, in a manner as hereinafter set forth, a device of the class referred to for protecting the edges of the walls and for reinforcing the corners of a carton of the corrugated paper type; for preventing the tie employed for maintaining the walls of the carton around the contents of the latter shifting from its initially set position; for protecting and concealing the tie at the corners of the carton; for preventing the crushing of the carton by the tie; for preventing the crushing of the corners of the carton by the tie; for preventing the carton from being distorted by the tie during the tying operation; for preventing the crushing of the contents of the carton by the tie during the tying operation and after the tie has had its ends anchored or secured together.

Further objects of my invention are to provide, in a manner as hereinafter set forth, a device for the purpose set forth which is simple in its construction, strong, durable, compact, readily installed with respect to a carton for conveniently receiving the tie for the latter, thoroughly efficient in its use and inexpensive to manufacture.

With the foregoing and other objects in view, my invention consists of such parts and such combination of parts as are hereinafter more specifically described and as illustrated in the accompanying drawing, wherein is shown an embodiment of the invention, but it is to be understood that changes, variations and modifications may be resorted to which fall within the scope of the invention as claimed.

In the drawing:

Figure 1 is a perspective view of the device extended prior to its application.

Figure 2 is a top plan view of the device extended prior to its application.

Figure 3 is a view looking towards one of the end edges of the device when extended.

Figure 4 is a view looking towards one of the side edges of the device when extended, and

Figure 5 is a fragmentary view, in perspective, of a corrugated paper carton, the tie for the latter and illustrating the installation of my carton edge protector and tie retainer with respect to the carton and tie.

Referring to the drawing, there is illustrated,

by way of example, for the purpose of showing the application of my device, the top and the end walls 6, 7 respectively of a corrugated paper carton and a tie 8 for maintaining the carton closed and for maintaining the walls of the latter in encompassing relation with respect to the contents, not shown, of the carton. One end of the wall 6 seats upon the top edge 9 of the wall 7. The edge of the latter is designated 10.

The carton edge protector and tie retainer device, in accordance with my invention, is formed from a rectangular foldable or bendable plate 11 of sheet metal of the desired gauge, having beveled side and end edges 12, 13 respectively.

The device includes a pair of rectangular wings 14, 15 disposed at right angles to each other and which, at their inner sides, merge into the sides 16, 17 of a rounded coupler 18 which is outset at an inclination with respect to the inner sides 19, 20 of the wings 14, 15 respectively. The coupler 18 forms a groove 21 for receiving the edge 10 of wall 6. The wing 14 is horizontally disposed and the wing 15 is vertically disposed. The wings 14, 15 are positioned against the outer faces of the walls 6, 7 respectively.

The wing 14 is formed with a pair of oppositely disposed aligning V-shaped slits 22 extending lengthwise thereof. The material freed by the slits 22 is bent inwardly at right angles to the body of the wing 14 to provide a pair of V-shaped fastener bars 23 for extension into the wall 6 for anchoring wing 14 thereupon.

The wing 15 is provided with a pair of spaced parallel V-shaped slits 24 extending transversely thereof. The material freed by the slits 24 is bent inwardly at right angles to the body of wing 15 to provide a pair of V-shaped fastener bars 25 for extension into the wall 7 for anchoring wing 15 thereupon. Preferably the bars 25 will be of less area than the bars 23.

The wings 14, 15, on the transverse medians thereof and in proximity to the sides 19, 20 respectively, are provided with the circular openings 26, 27 respectively for the passage of the stretch 28 of the tie 8. The stretch 28 passes 45 under the coupler 18 and is protected by and substantially concealed by the latter. The walls of the openings 26, 27 prevent the shifting of the stretch 28 laterally upon the corner of the carton after the tie has been set and strung 50 through wings 14, 15.

The coupler 18 preferably is formed with a row of spaced openings 29 to facilitate the rounding thereof.

It is to be understood that the carton will 55

be provided at each end with one of the devices arranged in the manner as shown in Figure 5. The devices, when anchored in position upon the carton, will prevent the crushing of the corners and walls of the carton by the tie due to the manner in which the tie is strung through and arranged relative to the wings 14, 15, that is to say, the stretches 28 of the tie are arranged under the couplers by the passage of such stretches through the openings 26, 27 and other stretches 30, 31 bear against the outer faces of the wings 14, 15. As the devices not only prevent the crushing of the corners of the carton, but also the crushing or distorting of the walls of the carton, it naturally follows that the contents of the carton are not crushed or distorted.

What I claim is:

1. A carton edge protector and tie retainer device comprising a pair of spaced wings disposed at an angular relation, a rounded coupler integral at its sides with the inner sides of and outset with respect to said wings, each of said wings being formed with an opening in proximity to its point of jointure with a side of said coupler, said wings having their openings extending in opposite directions with respect to each other, and each of said wings having right angularly disposed inwardly extending portions providing fastener barbs.
2. A carton edge protector and tie retainer comprising a pair of spaced wings disposed at right angles to each other and adapted to seat against a pair of walls of the carton, a coupler outset at an inclination with respect to, arranged between and integral at its sides with the inner sides of said wings, said coupler being rounded to form an inwardly arranged groove to receive a corner of the carton, said wings being formed with openings in proximity to their points of emergence with said coupler for disposing a stretch of the tie under said coupler, and each of said wings being formed with spaced inwardly extending fastener barbs for anchoring it to one of said walls.
3. A carton edge protector and tie retainer

comprising a pair of spaced wings disposed at right angles to each other and adapted to seat against a pair of walls of the carton, a coupler outset with respect to, arranged between and integral at its sides with the inner sides of said wings, said coupler being rounded to form an inwardly arranged groove to receive a corner of the carton, said wings being formed with openings in proximity to the sides of the coupler for disposing a stretch of the tie under said coupler, one of said wings having lengthwise portions thereof providing fastener barbs for anchoring it to one of said walls, and the other of said wings having transverse portions thereof providing fastener barbs for anchoring it to the other of said walls.

4. A carton edge protector and tie retainer device comprising a pair of spaced wings, a rounded coupler integral at its sides with the inner sides of and outset at an inclination with respect to said wings, each of said wings being formed with an opening in proximity to the side of the coupler, and each of said wings having right angularly disposed inwardly extending portions providing fastener barbs, the barbs of one wing being disposed at right angles to the barbs of the other wing.

5. A carton edge protector and tie retainer comprising a pair of spaced wings disposed at right angles to each other and adapted to seat against a pair of walls of the carton, a coupler outset with respect to, extending in a plane at an inclination to, arranged between and integral at its sides with the inner sides of said wings, said coupler being rounded to form an inwardly arranged groove to receive a corner of the carton, said wings being formed with openings in proximity to the sides of the coupler extending in directions at right angles to each other for disposing a stretch of the tie under said coupler, each of said wings being formed with a pair of spaced fastener barbs for anchoring it to one of said walls, the barbs of one wing being disposed at right angles to the barbs of the other wing.

LUIS OCHOA VIZCAINO. 45
